UNITED STATES PATENT OFFICE.

ROBERT S. BOLGER, OF RICHMOND HILL, NEW YORK, ASSIGNOR OF ONE-HALF TO
GEORGE F. WHISTLER, OF BROOKLYN, NEW YORK.

PAPER BARREL.

1,302,128.

Specification of Letters Patent. Patented Apr. 29, 1919.

Application filed March 23, 1916, Serial No. 36,121. Renewed January 2, 1919. Serial No. 269,390.

To all whom it may concern:

Be it known that I, ROBERT S. BOLGER, a citizen of the United States, residing at Richmond Hill, in the county of Queens 5 and State of New York, have invented new and useful Improvements in Paper Barrels of which the following is a specification.

This invention relates to barrels, the main object of the invention being to produce a 10 reinforced barrel the body of which is composed of a continuous web of flexible material such as paper or the like in any of the forms thereof capable of being expanded or stretched for the purpose of producing 15 a barrel body of the bilged type or, in other words, a barrel body in which the ends are of less diameter than the center, the same as the ordinary wooden barrel of staved formation now in common use.

With the above and other objects in view, 20 the invention consists in the novel construction, combination and arrangement of parts, as herein described, illustrated and claimed.

In the accompanying drawings:

Figure 1 is a plan view of a partially 25 corrugated web of material from which the body of the barrel is made.

Fig. 2 is a section on the line 2—2 of Fig. 12.

Fig. 3 is a section on the line 3—3 of 30 Fig. 12.

Fig. 4 is an edge view of the web after being corrugated.

Fig. 5 is a side elevation of the completed 35 barrel, partly broken away in diametrical section to better illustrate the construction thereof.

Fig. 6 is a plan view looking toward the head or top of the barrel body.

Fig. 7 is a fragmentary vertical section 40 through the head portion of the barrel showing the hoop receiving and head supporting means.

Fig. 8 is a plan view of the barrel head 45 partly broken away to illustrate the construction thereof.

Fig. 9 is a fragmentary diametrical section through the head on the line 9—9 of Fig. 8.

Fig. 10 is a section on the line 10—10 of 50 Fig. 1.

In producing a barrel in accordance with the present invention, a web of paper indicated at 61 is first dampened in order that it 55 may be stretched. It is then passed through

a suitable machine and the web is stretched longitudinally between the side margins thereof, the central or medial portion of the web being stretched to the greatest extent and the stretching of the web then diminishing toward the side or longitudinal margins thereof. The web after being dampened and stretched in the manner referred to is wrapped around a form or mandrel, an adhesive being applied to the web 60 as it is wrapped around the mandrel and upon itself to form superimposed plies or layers and rolling pressure being applied to the initial and subsequent convolutions or wrappings of the web as they are wrapped 65 around the mandrel.

In the description of the article, the body of the barrel is made up of a web 61 of paper wound around a mandrel to produce a plurality of superimposed plies or layers 70 of 75 material (see Fig. 5) wrapped in contact with an adhesively united or attached to each other. Between the layers of material may be placed strips or bands 66 of a like or unlike material. The interposed strips or 80 bands not only act as strengthening means, but in addition create an annular enlargement or bulge of the walls in an outward direction at these points. At the intermediate points where the additional material is placed, 85 a hoop or band 66' may be crimped over both edges of the annular protuberance. At the extremities or the head ends of the barrel, they create a shoulder or gripping edge for the turned in or curled edge 67 of the outer 90 chine hoop 68 of the head holding means. This outer hoop acts as a retaining medium for an inner hoop 69, having an annular inclined wall 70 below which may be inserted a wire hoop 71 in the retaining channel 72. 95 Below the wire hoop retaining channel is a head receiving seat 73, having an annular head supporting lip 74 from which the walls of the hoop return toward and rest against the inner surface of the body of the barrel. 100

At the center of the barrel or bilge section is placed an internal hoop, the construction of which is best shown in Fig. 5. Before being entered into the barrel, this hoop is of a W cross section, with the long legs 75 at 105 the center and two shorter legs 76 toward the extremities. After the hoop is inserted in the barrel, pressure is applied to the legs 75 causing them to assume a U shape, as shown in full lines. This distortion increases the 110

outer diameter of the hoop so as to cause the same to crowd against the inner walls of the barrel, and in this manner prevents its dislodgment during usage.

5 In Fig. 6 is shown in dot and dash lines the wire hoop 71 in a distorted formation. To insert this wire hoop, one edge is crowded under the projecting lip 77 of the head retaining hoop, and as the pressure is 10 applied circumferentially, the hoop 71 assuming its natural or circular formation is by this pressure or crowding action forced into the channel 72, thereby crowding the upper layer or disk 78 of the head downward, also forcing the lower or cup shaped disk 79 of the head over the corner 80 of the head receiving hoop.

It will be noticed by referring to Fig. 9, 20 that the lower disk 79 of the head is slightly flared and larger in diameter than the receiving seat 73 of the hoop, also that normally the top disk 78 of the head is a flat disk of material.

It is then obvious that the crowding of 25 the wire hoop 71 into the channel 72 will cause the head to crowd against the corner 80 against the wall 73, and against the wire hoop 71, thereby forming a perfect closure of the barrel by the head.

30 In the inner hoop or head receiving means of the barrel, on the inclined face 70, will be noted a depression 81, into which, for the removal of the head holding wire hoop, may be inserted any pointed instrument such as a screw driver or other tool, an inward pressure of which will force or pry the wire hoop from its seat, after which it may be readily sprung into a distorted shape and removed, leaving the head free 40 to be taken out.

The external offsets formed by the circumferential strips incorporated between the plies of the barrel body serve to resist and withstand internal outward pressure 45 while a bilge sustaining band within the center of the barrel body serves to withstand external inward pressure. All of said bands thus mutually contribute to reinforce and strengthen the barrel and render the 50 same practical for heavy duty service. The chine forming band also assists the other bands in the same way and for the same purpose, thus producing a very strong and practical paper barrel of the closed or 55 perforate type.

Having thus described my invention, I claim:—

1. A bilged barrel body composed of a continuous web of paper wrapped upon itself to form a barrel body embodying a

plurality of superimposed plies, and a bilge-sustaining expansion ring located within the barrel body and midway between the ends thereof, said ring being expansible after its insertion in the barrel body. 65

2. A bilged barrel body composed of a continuous web of sheet material of sufficient length to form a barrel body embodying a plurality of superimposed layers, a strip interposed between the layers and producing an annular reinforcing offset, and a self-retaining binder encircling said offset. 70

3. A bilged barrel body composed of a continuous web of sheet material of sufficient length to form a barrel body embodying a plurality of superimposed layers, a strip interposed between the layers and producing an annular reinforcing offset, and an annular binder encircling said offset and having a barrel head supporting portion 75 extending into the end of the body.

4. A bilged barrel body composed of a continuous web of paper wrapped upon itself to form a barrel body embodying a plurality of superimposed plies, a strip extending circumferentially of the body and interposed between the plies thereof and producing an annular reinforcing hoop-like offset, and a binder encircling said offset. 85

5. A bilged barrel body composed of a continuous web of paper wrapped upon itself to form a barrel body embodying a plurality of superimposed plies, a strip extending circumferentially of the body interposed between the plies thereof and producing an annular reinforcing hoop-like offset, and a bilge-sustaining expansion ring located within the barrel body and midway between the ends thereof. 95

6. A bilged barrel body composed of a continuous web of paper wrapped upon itself into barrel formation, a strip extending circumferentially of the end of the body and interposed between the wrapped plies thereof producing an external hoop-like offset, and a chine band embracing the adjacent edge of the body and having an outer portion which embraces, engages and is retained by said offset and also having an inner portion which lies within the barrel 105 body and is formed with a barrel head receiving seat and also an annular groove to receive a barrel head retaining hoop. 110

In testimony whereof I affix my signature in presence of two witnesses.

ROBERT S. BOLGER.
